LOUVER DAMPER

Howard J. Young, River Forest, Ill., assignor to
The Powers Regulator Company, Chicago, Ill.,
a corporation of Illinois

Application January 2, 1936, Serial No. 57,120

5 Claims. (Cl. 98—110)

My invention relates to dampers and particularly to dampers of the type composed of a plurality of parallel pivoted blades.

It has long been recognized that in the operation of dampers of the type described, it is desirable to avoid angularity relative to the stream of air being delivered through the damper in partly opened position. This occurs when all the blades are pivoted to swing in the same direction, the result being that the stream of air is deflected laterally and not permitted to travel in a straight line. This is avoided by causing alternate blades to open in opposite directions, but suitable mechanism for accompanying this result has not heretofore been suggested.

In that connection it is desirable, in order to insure a tightly closed damper condition to overlap the edges of adjacent blades. However, where adjacent blades swing in opposite directions this has been found to be difficult if not impossible, due to interference between the overlapped edges at the start of the opening movement.

I have designed and perfected a mechanism that permits the use of the ideal form of damper blades and to operate the blades in the desired manner without interference. This is accompanied by utilizing the eccentric motion of two angularly disposed cooperating arms.

The invention will be more readily understood by reference to the accompanying drawing; in which,

Fig. 1 is an elevation of a damper constructed in accordance with my invention;

Fig. 2 is a sectional view on the line 2—2 of Fig. 1; and,

Fig. 3 is a similar view with the blades in open position.

In the drawing I have illustrated a small model having only four blades. It will be understood, however, that the invention may be applied to a damper of any desired size or number of blades.

In the drawing, the damper is illustrated as consisting of an angular frame 10, having side stop flanges 11. Each of the four blades 12, 13, 14, 15 carries a pintle 16 at each end, seated in suitable openings in the frame 10 and acting as pivots arranged at the central longitudinal axis of the blades.

It will be noted that by reason of the arms 17, 18 and the link 19, the blades 12, 14 are caused to swing with the same motion, that is, in the same direction; further, that as the result of the arms 20, 21 and the link 22, the blades 13, 15 have corresponding uniform motion. It will be

noted also that the edges or margins of the blades overlap as shown in Fig. 2. With this arrangement adjacent blades could not swing toward open position without conflict at their margins, but this is avoided by the means about to be described.

The actuating member or link 23, shown in dotted lines in Figs. 2 and 3, is connected to an ear 24 mounted at one side of the pivot point of the blade 14, this link being actuated by a motor of some kind in the usual manner. It will be seen that a thrust on the link 23 will tend to swing the blade 14 into the position shown in Fig. 3. Connected to the blade 14 at a point adjacent to the ear 24 is an arm 25 carrying a pin or bolt 26 at the outer end thereof. A similar arm 27 is connected to the blade 13, in this instance the connection being to the pivot or pintle 16 which is rigid with the blade through the set bolt 28. The arm might be connected to the blade in other manners than that shown. It will be noted that the arms 25, 27 are arranged at converging angles, the arm 27 having a slot 29 cooperating with the pin 26 in the end of the arm 25. Due to the angularity of the arms, the early part of the angular movement of the blade 14 from the position of Fig. 2 toward that of Fig. 3 results in very slight angular movement of the blade 13, the movement increasing however, as the opening movement continues. This is because the pin 26 is traveling almost exactly lengthwise of the slot 29. This permits the overlapped edges of the blades to separate and thereby avoid interference, the movement of the blade 13 accelerating as the action continues. On the closing motion the described action is reversed, the blade 13 being practically closed somewhat ahead of the blade 14. It will be noted that the described movement of the blades 13, 14 is duplicated in all the other blades making up the damper, due to the cross connection by means of the links. As a result the desired damper opening is provided and a complete and tight closing of the blades is insured, due to the overlapping.

As above stated, the device shown in the drawing is illustrative of the principle, and changes and modifications therein will readily suggest themselves to others to meet required conditions.

I claim:

1. In a louver damper, the combination of pivoted blades, adjacent blades being mounted to swing in opposite directions, links connecting alternate blades whereby to effect duplication of motion thereof, an actuating arm connected to one blade for effecting movement thereof, an

- arm projecting at an angle from the plane of the face of the actuated blade, a second arm projecting at an angle from the face of an adjacent blade, said arms having a pin and slot connection whereby the movement of the actuated blade is transmitted eccentrically to said adjacent blade.
2. In a damper, the combination of a plurality of parallel pivoted blades, adjacent blades having their edges overlapped when in closed position and adjacent blades being mounted to swing in opposite directions, links connecting alternate blades whereby to effect duplication of motion thereof, a member connected to one blade for actuating the same, an arm projecting at an angle from the plane of the first of the actuated blades, a second arm projecting at an angle from the face of an adjacent blade, said arms having a pin and slot connection whereby the swinging movement of the driven blade is eccentric relative to the said actuated blade.
3. In a damper, the combination of a plurality of parallel pivoted blades, adjacent blades having their edges overlapped when in closed position and adjacent blades being mounted to swing in opposite directions, links connecting alternate blades whereby to effect duplication of motion thereof, a member connected to one blade for actuating the same, a pair of arms one connected to each of two adjacent blades, said arms projecting toward each other and forming a V with the blades in closed position, a pin in the end of one arm cooperating with a slot in the other arm whereby the blade that carries the arm with the pin may swing

more rapidly toward an open position at the beginning of the opening movement than the blade carrying the slotted arm whereby the overlapped edges are noninterfering.

4. In a damper, a combination of a plurality of parallel blades pivoted on their central longitudinal axis adjacent blades being mounted to swing in opposite directions, means connecting alternate blades whereby to effect motion in the same direction, a driven thrust arm connected to one blade at one side of its pivot for swinging said blade, an arm fixed to said actuated blade and projecting at an angle therefrom, a cooperating arm projected from an adjacent blade and arranged to converge into cooperating relation with said first arm, one of said arms having a pin and the other a slot whereby the so connected blades are caused to swing in opposite directions, the eccentricity of movement of said arms causing accelerated motion of one blade at the beginning of the opening movement of said blades.

5. In a louver damper, the combination of pivoted blades, adjacent blades being mounted to swing in opposite directions, an actuating arm connected to one blade for effecting movement thereof, an arm projecting at an angle from the plane of the face of the actuated blade, a second arm projecting at an angle from the face of an adjacent blade, said arms having a pin and slot connection whereby the movement of the actuated blade is transmitted eccentrically to said adjacent blade.
